(57) **CLAIM**

The ornamental design for a poultry feeder or drinker as shown and described.

DESCRIPTION

FIG. 1 is a perspective view of a poultry feeder or drinker; FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In these drawings, the solid lines illustrate the claimed ornamental design, whereas the broken lines, if present, illustrate unclaimed subject matter and form no part of the claimed design.

1 Claim, 7 Drawing Sheets
